UNITED STATES PATENT OFFICE.

LEONARD R. STEEL, OF CLEVELAND, OHIO.

WATER-COOLER.

1,004,490.

Specification of Letters Patent. Patented Sept. 26, 1911.

Application filed November 11, 1910. Serial No. 591,806.

To all whom it may concern:

Be it known that I, LEONARD R. STEEL, a citizen of the United States of America, residing at Cleveland, in the county of Cuyahoga and State of Ohio, have invented new and useful Improvements in Water-Coolers, of which the following is a specification.

This invention relates to water coolers.

It is common in the present practice to employ coolers wherein purified or distilled water is placed into bottles and the bottle mounted on a stand from which the water from the bottle circulates in coils, metal chambers or the like. This establishes an unsanitary condition in that the water becomes somewhat stagnant and contaminated with germs and the water is in a more unsanitary condition than before it was filtered.

It is an object in the present invention to provide means whereby the water can be delivered direct from the bottle and in the invention to be hereinafter more fully described, means are employed wherein the ice packing wholly surrounds the body of the bottle, the chamber for the ice being perforated and being arranged in direct communication with a drain chamber which is constructed so as to allow the water to freely circulate around that portion of the bottle immediately adjacent its discharge end.

Another object of the invention is to provide a novel construction of bottle which can be conveniently and quickly associated with the cooling chamber.

Another object is to provide the bottle with a vent opening which is located in the bottom of the bottle, the said bottle being constructed so that the vent opening is above the lowest point of the bottle when the latter is in an upright position.

In the drawings, forming a portion of this specification and in which like numerals of reference indicate similar parts in the several views:—Figure 1 is a vertical section through the cooler. Fig. 2 is a perspective view of a portion of the neck of the bottle showing the nipple removed therefrom. Fig. 3 is a similar view showing the nipple attached to the neck. Fig. 4 is a section of a portion of the bottle showing the cap for the vent passage.

The invention embodies a casing comprising an outer jacket 1 and an inner jacket 2 which are spaced apart by a non-heat conducting material 3. The inner jacket is

closed by a bottom-forming member 4 which is provided with a peripheral flange 5 embracing the jacket 2 and a horizontal seat-forming flange 6 which extends inwardly from the jacket 2, as shown. At the top, the jacket is formed to provide an outwardly extending flange 7 and an upwardly extending flange 8, which latter has secured thereto the peripheral flanged end 9 of the upper end of the outer jacket 1. The outwardly extending flange 7 forms a shoulder which is arranged substantially in step-like manner to the shoulder 10 formed by the bent peripheral upper end of the outer jacket. The outer jacket extends downwardly below the plane of the inner jacket, and as illustrated, a bottom-forming member 11 closes the bottom of the outer jacket and it is disposed in spaced relation to the bottom 4, a packing of non-heat conducting material 12 being interposed between the bottoms 4 and 11 respectively. The bottom member 11 is formed on its peripheral edge to provide a flange 13 which embraces the outer jacket. At the center, the bottom member 11 is formed with an opening 14 from which extends a collar 15 which is secured to the depending collar 16 at the center of the bottom member 4.

An ice chamber 17 is removably mounted within the inner jacket. This chamber comprises an outer vertically disposed wall 18 and an inner vertically disposed wall 19. The lower ends of the walls 18 and 19 are offset and formed to provide depending flanges 20 which are secured to the flange 21 of the perforated bottom 22. The bottom 22 rests directly upon the seat 6 formed upon the bottom member 4. This construction is desirable so that the bottom 22 is spaced from the bottom member 4 so as to form a drain space 23. A horizontally disposed bottle rest 24 is formed with an upwardly curved peripheral portion 25 which is countersunk in the offset 26 formed at the lower end of the inner wall 19, and as illustrated, the said peripheral portion lies flush with the member 19 for a purpose to be hereinafter described. The bottle rest is apertured at its center, as shown at 26', and it is formed at this point to provide a depending collar 27 which fits within the collar 15 and which is secured thereto in any suitable well known manner, preferably by solder.

The construction of the ice chamber is such that the inner wall 19 thereof provides

a chamber 28 for the bottle 29'. At one end the bottle is formed with a neck 29. When the bottle is inverted and operatively associated in the chamber 28 the neck 29 extends downwardly into the opening 14. The neck is formed with an annular series of depressions or notches 30 in which the radial lugs 31 on the male member or nipple 32 of a coupling 33 are formed. The lugs are preferably cemented in the notches or recesses 30 so that the male member of the coupling will be held against displacement from the neck of the bottle. By providing the recesses 30 and the lugs 31, the male member of the coupling will be held against rotary movement on the bottle neck. When the bottle is operatively mounted in the chamber 28 it is supported wholly by the rest 24.

The female member 34 of the coupling 33 is provided with the interiorly threaded socket 35 to receive the exteriorly threaded portion of the male member 32 which extends upwardly into the opening 14 at the center of the bottom member 11. The female member of the coupling is detachably threaded to the short extension 36 of the draw-off faucet 37. The bottom members 4 and 11 respectively, are formed with alining passages 38 and mounted in such passages 30 is a drain pipe 39. The drain pipe is provided with a suitable draw-off valve 40. The bottom of the bottle is of concavo-convex form so as to present on the underside of the bottle immediately at the center thereof a relatively large concavity 41. The bottom of the bottle is provided at its center with an exteriorly threaded nipple 42 which is formed with an air vent passage 43. As shown in Fig. 4 of the drawings, the nipple 40 has detachably connected therewith an interiorly threaded cap 44 having a packing 45 of cork or the like in its head portion 46. A rubber gasket 47 surrounds the nipple and when the cap is tightly adjusted on the nipple it bears frictionally against the gasket 47 and the packing 45 is brought to bear directly against the end of the nipple.

The chamber 28 for the bottle is of a size which will permit the bottom of the bottle when the bottle is inverted to be disposed slightly below the plane of the flanged end 7 of the inner jacket. A closure 48 is provided for the casing, and as shown, it consists of a head 49 and a similar head 50. The heads are spaced apart to receive a filling of non-heat conducting material 51. The head 50 is formed with a peripheral step portion presenting shoulders 52 and 53 respectively, to be seated against the shoulders 7 and 10 respectively, at the top of the casing. The closure is provided with a suitable handle 54. The inner wall 19 of the ice chamber 17 is stamped to form eyes 55 with which handles 56 are pivotally engaged.

In inserting a full bottle in the chamber 28, the bottle is set in an upright position, after which, the casing of the cooler is inverted and placed over the bottle so as to cause the neck of the bottle to extend through the opening 14. After this has been done the female member of the coupling 33 is engaged with the male member 32 of the coupling. When these parts are properly assembled with each other the cooler is placed in its operative position, after which, the ice chamber 17 is inserted in the chamber so as to wholly surround the bottle. The cap 44 of the bottle is removed so as to permit the required quantity of air to enter the bottle on the displacement of liquid therefrom. When the closure 48 is closed against the casing a most desirable air tight joint is formed between the closure and the casing to exclude the air from the ice chamber. In removing an empty bottle from the cooler the faucet 40 is first opened to permit the water to be thoroughly drained from the ice chamber 17 and from the drain or refrigerating space 23. The cover of the cooler and ice chamber respectively, are then removed and the cooler is inverted so as to permit the operator to separate the faucet 37 from the neck of the bottle. A bottle constructed as described while being extremely desirable for use in connection with the specific cooler described, will be found most desirable when used in connection with other well known forms of coolers.

From the construction of the cooler it will be seen that I provide means confining the refrigerant, such as ice, wholly around the bottle. The drain chamber 23 which is in direct communication with the ice chamber allows the weight of water from the ice to circulate about the collar 27 which will tend to a considerable extent to cool that portion of the bottle immediately adjacent the discharge end thereof. In this instance, the chamber 23 wholly surrounds a portion of the neck.

I claim:

1. A water cooler comprising a casing having an opening therein at one end, a water receptacle located in the casing and spaced from the walls thereof and provided at one end with a neck portion which extends through the opening in the casing, a rest located in the casing and wholly supporting the said water receptacle, and a depending collar formed on the rest and extending into the opening in the casing.

2. A water cooler comprising a casing having an opening therein at one end, an ice container located in the casing and provided with a perforated bottom portion which is spaced from the bottom of the casing so as to form a drip chamber, and a water receptacle removably mounted in the

- casing and surrounded by the said ice container and provided at one end with a neck portion which extends into the opening in the casing.
5. 3. A water cooler comprising a casing formed upon its bottom with a shoulder, an ice container removably mounted in the casing and supported by the said shoulder, the said casing having an opening therein at 10 one end, and a water receptacle removably mounted in the casing and wholly surrounded by the ice container and having a discharge outlet disposed in line with the outlet of the casing.
15. 4. A water cooler comprising a casing having an opening therein at one end, a water receptacle removably mounted in the casing and provided with a neck portion which extends into the opening in the casing, 20 an ice container removably mounted in the casing and substantially wholly surrounding the water receptacle, means in the casing for supporting the ice container and holding the same with its bottom spaced from the bottom of the casing so as to form a drip chamber beneath the container and the receptacle, the bottom of the said container being perforated so as to establish commu-

nication between the drip chamber and the ice container, and a discharge faucet de- 30 tachably connected with the casing and with the water receptacle.

5. A water cooler comprising a casing provided with an opening at one end and with a removable closure at its opposite end, 35 an ice container located in the casing and provided with inner and outer vertically disposed walls and a connecting bottom, a rest wholly supported by the casing, the inner wall of the said ice container being provided with an outwardly extending offset portion, the said rest having a portion 40 thereof fitted in the offset portion of the inner wall of the ice container, and a receptacle removably mounted in the casing 45 and supported upon the rest and wholly surrounded by the inner wall of the ice container and provided with a discharge outlet located in line with the outlet of the casing. 50

In testimony whereof I affix my signature in presence of two witnesses.

LEONARD R. STEEL.
